(57) **CLAIM**

The ornamental design for a heads up display for swimming goggles, as shown and described.

DESCRIPTION

FIG. 1 is a front view of a heads up display for swimming goggles according to our new design.

FIG. 2 is a top view of the heads up display for swimming goggles of FIG. 1.

FIG. 3 is a rear view of the heads up display for swimming goggles of FIG. 1.

FIG. 4 is a bottom view of the heads up display for swimming goggles of FIG. 1.

FIG. 5 is a right side view of the heads up display for swimming goggles of FIG. 1.

FIG. 6 is a left side view of the heads up display for swimming goggles of FIG. 1.

FIG. 7 is a front-top isometric view of the heads up display for swimming goggles of FIG. 1.

FIG. 8 is a front-bottom isometric view of the heads up display for swimming goggles of FIG. 1.

FIG. 9 is a rear-top isometric view of the heads up display for swimming goggles of FIG. 1; and,

FIG. 10 is a rear-bottom isometric view of the heads up display for swimming goggles of FIG. 1.
